UNITED STATES PATENT OFFICE.

HERMAN E. PROMNITZ, OF DAYTON, KENTUCKY.

DESIGN FOR A BADGE.

SPECIFICATION forming part of Design No. 36,409, dated July 7, 1903.

Application filed April 11, 1903. Serial No. 152,270. Term of patent 7 years.

To all whom it may concern:

Be it known that I, HERMAN E. PROMNITZ, a citizen of the United States of America, and a resident of Dayton, in the county of Campbell and State of Kentucky, have invented a certain new, original, and ornamental Design for a Badge, of which the following is a specification.

In the accompanying drawing I have shown a front elevation of a society emblem consisting of an elk's head, the antlers of which form the words "The Elks."

What I claim is—

The new, original and ornamental design for a badge as shown.

HERMAN E. PROMNITZ.
